UNITED STATES PATENT OFFICE.

CHARLES H. LAVIS, OF PHILADELPHIA, PENNSYLVANIA.

IMPROVED MACHINE FOR LOADING METALLIC CARTRIDGE-CASES.

Specification forming part of Letters Patent No. 43,780, dated August 9, 1864.

To all whom it may concern:

Be it known that I, CHARLES H. LAVIS, of Philadelphia, in the county of Philadelphia and State of Pennsylvania, have invented a new and useful improvement on the machine for loading metallic cartridges by cutting a groove in the under face of the loading-wheel and fastening to the bed-plate a block having on its upper face one or more inclined planes and one or more resting-flats. The groove cut in the under face of the loading-wheel is for the purpose of receiving the block and giving the shells of the cartridges sufficient space to raise and lower. The block is for raising the shells of the cartridges, first, on a level with the face of the loading-wheel for receiving the ball, and, second, to raise the shells of the cartridges a sufficient distance above the face of the loading-wheel to allow of crimping or tightening the shell to the ball; and I do hereby declare that the following is a full, clear, and exact description of the construction and operation of the same, reference being had to the annexed drawings, making a part of this specification, in which—

Plate 1, (plan view,) Figure A represents the bed-plate; Fig. B, the loading-wheel; *p*, the holes in the loading-wheel for inserting the shells of the cartridges; *n*, the stud around which the loading-wheel revolves. In Plate 2 (plan view) Fig. B is the under face of the loading-wheel, in which the groove *l* is cut, (as claimed.) In Plate 4 *m* is a side view of the block, showing the inclined planes *a* and *b* and the resting-flats *c* and *d*. Plate 5 is a vertical section of the loading-wheel B, showing the holes *p* filled with shells *s* of the cartridges, the block *m*, with the inclined planes *a* and *b*,

and the resting-flats *c* and *d* on it, also a side view of the bed-plate A.

Upon the revolution of the loading-wheel (Plate 5) the shell of the cartridge *s* is carried up the first inclined plane *a* of the block *m* to the first resting-flat *c*. This brings the rim of the shell of the cartridge *s* on a level with the upper face of the loading-wheel B, where the ball is inserted into it. By the further revolution of the loading-wheel B the same cartridge-shell *s* is carried up the second inclined plane *b* of the block *m* to the second resting-flat *d*, where the shell of the cartridge projects a sufficient distance above the upper face of the loading-wheel to allow of crimping or tightening the shell to the ball, which completes the cartridge.

By the old method of making cartridges loading-wheels of different thicknesses were used suited to the different lengths of cartridge required. I use the same loading-wheel for all cartridges, merely using blocks of such heights as are suited to the lengths of cartridge required.

What I claim as my invention, and desire to secure by Letters Patent, is—

Cutting a groove, *l*, in the under face of the loading-wheel B, and fastening a block, *m*, with one or more resting-flats, *c* and *d*, and one or more inclined planes, *a* and *b*, on its upper face to the bed-plate A, the groove and block being arranged with reference to each other substantially in the manner as and for the purpose herein described.

CHARLES H. LAVIS.
